UNITED STATES PATENT OFFICE.

LIONEL C. TATE, OF NEWBURGH, INDIANA.

PLUG.

Application filed January 14, 1925. Serial No. 2,406.

This invention contemplates the provision of a fuse plug, wherein use is made of a fuse holder designed to support a plurality of fuses adapted to be singly and automatically arranged in a position for use, when a particular fuse is blown or impaired, the invention accomplishing the desired result in such quick order that the light will scarcely flicker.

10 Another important object of the invention resides in the provision of means for automatically limiting the movements of the fuse proper for use, with a view of preventing all of the fuses on the holder from being 15 destroyed by a trouble, other than the momentary increase in amperage, which trouble of course must be eliminated in the usual way.

More specifically stated, the invention 20 aims to provide a fuse plug designed to replace the character of plug now used in light and power circuits, and which plug makes use of a fuse holder mounted for rotation, and designed to support a plurality of fuses 25 to be used singly, means being provided for automatically turning the holder to bring the next fuse in order into a position for use, after the particular fuse has been destroyed by short circuit or an increase in amperage, while the invention also embodies 30 a means for locking the holder against movement after a predetermined number of fuses has been used and impaired to afford ample time to correct the trouble without wasting 35 the other fuses on the holder.

The nature and advantages of the invention will be better understood when the following detailed description is read in connection with the accompanying drawings, 40 the invention residing in the construction, combination and arrangement of parts as claimed.

In the drawings forming part of this application, like numerals of reference indicate 45 similar parts in the several views, and wherein:

Figure 1 is a view in elevation of the article forming the subject matter of the present invention.

50 Figure 2 is a top plan view.

Figure 3 is a sectional view taken on line 3-3 of Figure 2.

Figure 4 is an end elevation of the socket plug.

55 Figure 5 is a sectional view taken on line 5-5 of Figure 3, showing the normal

position of the fuse holder and the relation of the stop with the first fuse to be used.

Figure 6 is a similar view showing the 60 initial position of the fuse holder when the first fuse is arranged in engagement with the said stop.

Figure 7 is a perspective view of the co-operating parts of the fuse holder, showing 65 the parts separated.

Referring to the drawings in detail, 10 indicates generally the socket plug of ordinary well known construction which is threaded on the lower end of the stem 11 70 as clearly shown in Figure 3. The plug 10 is provided with the spaced contacts 12 at the end thereof, and which contacts are adapted to engage the contacts 13 carried by the fibre or insulated disk 14. This disk 75 is supported upon the stem 11 and has its underside recessed to receive the adjacent end of the socket plug 10 as shown in Figure 3. Also supported upon the stem 11 adjacent the upper end thereof is a similar disk 15. These disks are formed with grooves 16 to receive the adjacent ends of a hollow tubular member 17 constituting the body of the casing or enclosure in which the fuse holder is arranged, this casing being 80 85 preferably constructed of mica or the like.

Arranged within the casing 17 and reposing upon the lower disk 14 thereof is an annulus 18 of metal, clearly shown in Figure 7, and which annulus is secured to the disk 17 by suitable fastening elements 19 90 passed through apertured lugs or ears 20 forming part of the annulus. This annulus is formed with one of the contacts 13 reposing on the disk 14, to provide an electrical connection between one of the contacts 95 12 of the plug 10 and said annulus 18 as will be readily understood. The annulus 18 is split to provide a resilient portion 21, the purpose of which will be hereinafter described, and from which portion projects 100 an apertured ear 22. This annulus is also provided with a resilient contact portion 23 which is adapted to be engaged by a metallic disk 24 mounted upon the stem 11 for rotation thereon. This metallic disk 24 105 is thus electrically connected with the plug 10 through the instrumentality of the resilient contact 23 above mentioned, while adapted to repose upon the metallic disk 24 are headed fastening elements 25 utilized to 110 secure the metallic disk 26 to the bottom of the spool 27 constituting the fuse holder

above referred to. The fuse holder is mounted for rotation upon the stem 11 as clearly shown in Figure 3. The lower end of the spool being provided with openings 6 for the reception of the fuse wires 28, while the corresponding upper ends of these wires or fuses are adapted to be received by semi-cylindrical members 29, depending from the upper end of the spool as clearly shown in 10 Figure 7. Upon reference to Figure 3, it will be noted that upon the disk 14 forming part of the casing in which the movable parts are arranged, is an upright standard 30, and carried by the upper end of this 15 standard is a right angularly disposed pivoted stop 31 adapted to project in this space between the adjacent fuse wires 28 as clearly shown in Figure 3. Now, when one of these wires is arranged in contacting engagement 20 with the stop 31, the current passes through the plug 10 into one of the contacts 13, which contact engages the annulus 18, through which the current passes into the metallic disk 24, and thence to the metallic 25 disk 26 which is arranged upon the bottom of the spool 27 and held associated therewith by the metallic headed elements 25, the latter reposing upon the disk 24 for this purpose. The current then passes through 30 the particular fuse wire 28 being used through the stop 31, and thence through the post or upright 30 to the other contact 13 carried by the disk 14, which contact engages the adjacent contact 12 of the plug 10 35 returning the current through the plug as will be readily understood.

As above stated, it is the purpose of this invention to automatically arrange the fuse wires 28 in contacting engagement with the 40 stop 31, to complete the circuit, when the particular fuse wire being used has become impaired from any cause whatsoever. To accomplish this object, both the disk 24 and the fuse holder 27 are mounted for rotation upon the stem 11, and are adapted to rotate in unison being connected for this purpose by means of the lug 32 carried by the fuse holder, and which lug is adapted to be received by an opening 33 formed in 45 the disk 24. The disk 24 is connected with one end of a spring 35 which is coiled about the stem 11, and has its other end connected in any suitable manner with the disk 14, this end being indicated at 36 and preferably arranged within the opening 37 clearly shown in Figure 7. This disk 24 is split as at 38, and a portion of the disk bent downwardly to project beneath the lower surface of the disk to form an abutment 39, 50 there being preferably three of these abutments equi-distantly spaced from each other as shown in Figure 7. These abutments 39 are adapted to cooperate with the resilient stop 21 hereinabove referred to as forming 55 part of the annulus 18. Rising from the

apertured ear 22 which projects from the resilient stop 21 is a rod 40, this rod being associated with a hollow sleeve like member 41 arranged to slide within an opening formed in the disk 15 forming the top of 70 the casing above referred to, which arrangement of parts is illustrated in Figure 3. This rod 40 is utilized to depress the resilient stop 21 for moving it out of the path of the adjacent abutment 39 as the occasion 75 might require.

In practice, the fuse wires or fuses 28 are arranged upon the holder or spool 27 in the manner clearly shown in Figure 7, and the spool mounted upon the stem 11. The spool is then turned in a clock-wise direction upon the stem 11 to place the spring 35 under tension, the spool being limited in its movement in this direction by a lug 42 projecting from the periphery of the disk 24 coming in contact with the pin 43 rising from the disk 14. When the holder has been turned the limit of its movement for the purpose just stated, the resilient stop 21 engages one of the abutments 39, thus holding the disk 90 24 together with the spool or fuse holder 27 against retrograde movement under the influence of the spring 35. A pivoted stop 31 carried by the post or upright 30 is then swung to its active position in the space 95 between two adjacent fuses 28, this being the normal position of the post clearly shown in Figure 5. The device in its entirety is then placed in the fuse box by screwing the plug 10 to its socket, after which the rod 100 40 is depressed to move the stop 21 away from the adjacent abutment 39 thus allowing the spring 35 to turn the holder 27 the requisite distance in order to bring the adjacent fuse 28 in to contacting engagement 105 with the stop 31 and thus complete the circuit. The parts remain in this position as long as the particular fuse or wire 28 is susceptible of use, but just as soon as the particular fuse is blown or impaired beyond 110 further use by increasing the amperage or what not, the spring 35 functions to rotate the holder the requisite distance to bring the next fuse in order into contacting engagement with the stop 31, thus again completing the circuit which of course has been 115 broken by detriment to the fuse above mentioned. This operation takes place so rapidly that the next particular fuse is brought into use with scarcely a flicker of the light. It is 120 of course to be understood that the fuse holder can be constructed to accommodate any number of fuses, this of course depending upon the size of the plug.

Now, in order to prevent the blowing of 125 one fuse right after another until all of the fuses on the holder have been destroyed, which would of course occur in case there was a short in the light, I make use of the resilient stop 21 and the cooperating abut- 130

ment 39 forming part of the metallic disk 24. Consequently the destruction of a number of fuses in this manner, would give evidence of the fact that there is a short in the 5 light or other trouble which must be remedied immediately, and therefore the rotation of the fuse holder 27 is prohibited when the next abutment 39 on the disk is brought into engagement with the stop 21. 10 In other words, after the stop 21 has been initially depressed to allow the first fuse in order to contact the stop 31, moving from its normal position shown in Figure 5, to its initial position shown 15 in Figure 6, the resilient stop 21 resumes its normal position, that is immediately beneath the disk 24. So if the abutments 39 are spaced four fuses apart, four and only four fuses can be blown in successive order before the holder would be checked 20 in its movement by the next abutment 39 contacting the stop 21. The plug could then be removed until the trouble is remedied after which the plug is again arranged in the 25 socket, and the rod 40 depressed to release the holder for further operation. In this connection it might be stated that the abutments 39 can be spaced any particular distance apart, so that the holder would lock 30 after every one, two, three or four fuses are used, or after any number of fuses have been used in the manner mentioned, this depending upon the discretion of the user or manufacturer. It is manifest that the disk 35 15 can be easily removed from the casing, to allow the holder 27 to be subsequently removed for the purpose of replacing the fuse from time to time as the occasion may require. The size of the instrument in its 40 entirety will of course be determined according to the line with which it is to be used, it being obvious that a line with a high current requires a large instrument and heavier fuse wire. However, the article in its 45 entirety is very simple in construction and can be manufactured and sold at a very low cost, the working parts being visible while the automatic repeating action for the purpose of bringing the new fuse into use is particularly meritorious over fuse plugs in present 50 day use.

While it is believed that from the foregoing description, the nature and advantages of the invention will be readily apparent, I

desire to have it understood that I do not 55 limit myself to what is herein shown and described, and that such changes may be resorted to when desired as fall within the scope of what is claimed.

Having thus described the invention, I 60 claim:

1. A fuse plug of the character described comprising a casing, spaced contacts arranged therein, a metallic disk electrically connected with one of said contacts, and including a resilient contact and a resilient stop, a fuse holder comprising a stem mounted within the casing, a plurality of independent fuses supported on said holder, a stop contact adapted to be singly engaged 65 by said fuses to complete the circuit through the other of the said spaced contacts arranged within the casing, means for automatically turning the holder step by step, to bring each fuse into engagement with said 70 stop after the preceding fuse has become impaired beyond further use, and means carried by the stem and cooperating with said resilient stop to automatically lock the holder against further movement at predetermined 75 intervals. 80

2. A fuse plug of the character described comprising a casing, spaced contacts arranged therein, a metallic disk disposed within the casing and electrically connected 85 with one of said contacts, said disk including a resilient contact, and a resilient stop, a fuse holder including a stem mounted within the casing, a plurality of independent fuses supported on said holder, a stop contact electrically connected with the other of 90 said spaced contacts, and arranged to be singly engaged by said fuses to complete the circuit, means for automatically turning the holder step by step to bring each fuse 95 into engagement with said stop contact after the preceding fuse has become impaired, a metallic disk carried on said stem and constantly engaged by the resilient contact of 100 said disk, means carried by the disk on said stem and cooperating with said resilient stop to automatically lock the holder against rotation at predetermined intervals, and manually operable means for releasing the holder for further operation when desired. 105

In testimony whereof I affix my signature.

LIONEL CLARENCE TATE.
